(57) **CLAIM**

The ornamental design for a dual pouch for hair dye packaging, as shown and described.

DESCRIPTION

FIG. 1 is a perspective view of a dual pouch for hair dye packaging showing the claimed new design;

FIG. 2 is a front elevational view thereof;

FIG. 3 is a back elevational view thereof;

FIG. 4 is a left-side elevational view thereof;

FIG. 5 is a right-side elevational view thereof;

FIG. 6 is a top plan view thereof;

FIG. 7 is a bottom plan view thereof; and,

FIG. 8 is another perspective view thereof wherein the pouch is shown in a folded configuration.

The broken lines in FIGS. 1-3 and 8 represent a folding line along which the dual pouch for hair dye packaging is folded.
